United States Patent Office

Des. 190,937
Patented July 18, 1961

190,937

PLANETARY PHOTOGRAPHIC COPYING MACHINE

Frank A. Zagara, Rochester, N.Y., assignor to Eastman
Kodak Company, Rochester, N.Y., a corporation of
New Jersey

Filed Mar. 10, 1961, Ser. No. 64,216

Term of patent 14 years

(Cl. D61—1)

FIG.1.

FIG.2.

FIG. 1 is a front perspective view of a planetary photographic copying machine showing my new design; and FIG. 2 is a rear perspective view thereof.

I claim:

The ornamental design for a planetary photographic copying machine, as shown.
